OXIDATION OF PSEUDOSAPOPENINS

Monroe E. Wall, Oreland, and Samuel Serota, Philadelphia, Pa., assignors to the United States of America as represented by the Secretary of Agriculture

No Drawing. Application October 31, 1957
Serial No. 693,784

19 Claims. (Cl. 260—397.45)

(Granted under Title 35, U.S. Code (1952), sec. 266)

A non-exclusive, irrevocable, royalty-free license in the invention herein described, throughout the world for all purposes of the United States Government, with the power to grant sublicenses for such purposes, is hereby granted to the Government of the United States of America.

The conversion of sapogenins to 16-dehydropregnanes is achieved by a three-step process comprising converting the sapogenins to pseudosapogenins, oxidizing the pseudosapogenins to 16β -acyloxy pregnanes, and hydrolytically cleaving the 16β -acyloxy esters to obtain the 16-dehydropregnanes. By methods well known to those versed in the art the latter are useful intermediates for production of physiologically active steroids such as male and female sex hormones and cortisone.

The present invention relates to an improved process for oxidizing pseudosapogenins to 16β -acyloxy pregnanes.

The oxidation products referred to collectively as 16β -acyloxy pregnanes will in some instances include compounds, such as those with the steroid nucleus of diosgenin having a C-5(6) double bond, which should technically be called 16β -acyloxy pregnenes. For purposes of simplicity, one name will be used to refer to groups of compounds obtained by the process of this invention.

Previously the only known methods for converting pseudosapogenins to the corresponding 16β -acyloxy pregnanes involved oxidation in acid media. For example, the most commonly used system was chromium trioxide in acetic acid. Occasionally hydrogen peroxide in acetic acid has been used. Certain disadvantages are inherent in the use of acidic oxidation conditions. Acid sensitive groupings such as oxides are easily cleaved. Furthermore, when 16β -acyloxy pregnanes are produced under these acidic conditions, invariably some of the product is hydrolyzed to the 16-dehydropregnene. The latter in the presence of excess oxidant undergo undesirable reactions, thus lowering the yields.

A further disadvantage of the commonly used chromium trioxide-acetic acid system is that the 3-hydroxyl groups must be protected, as by acetylation, or they would otherwise be oxidized to 3-ketones. It has also been reported that chromium trioxide-acetic acid oxidation of unacetylated pseudosapogenins at times produces 20-hydroxy compounds. The process of the present invention may be used to oxidize unacetylated pseudosapogenins without causing these undesirable effects. At times it is desirable to oxidize unacetylated pseudosapogenins which are crystalline, easily purified compounds whereas pseudosapogenin acetates are oily and are difficult to purify.

The object of the present invention is to avoid the difficulties encountered by the oxidation of pseudosapogenins in acid media.

Another object of the present invention is to make new compounds, 16β -valeroxy pregnanes, unobtainable by previously reported oxidation processes.

It is well known to those versed in the art that pseu-

2

dosapogenins are quite stable to alkaline oxidation conditions. We have found a novel oxidizing system consisting of an aqueous solution of permanganate and metaperiodate ions which functions successfully under alkaline conditions.

According to the present invention a pseudosapogenin such as pseudosarsasapogenin, pseudosmilagenin, 11-oxo-pseudodiosgenin, 12-oxo-pseudodiosgenin, pseudodiosgenin, pseudotigogenin, 11-oxo-pseudotigogenin, and 16β -acyloxy pregnane is converted to the corresponding 16 β -acyloxy pregnane by a process comprising dissolving the pseudosapogenin in an inert, water soluble organic solvent not attacked by an alkaline oxidizing system, for example, dioxane, tetrahydrofuran, or tertiary butyl alcohol, and oxidizing the pseudosapogenin therein by mixing therewith an aqueous solution containing, based upon the weight of pseudosapogenin, about a 2 to 8 molar ratio of a water soluble alkali metal metaperiodate salt, such as sodium metaperiodate, about a 0.10 to 0.15, preferably 0.13 molar ratio of a water soluble alkali metal permanganate salt, such as potassium permanganate, and an alkaline agent to maintain a pH above 7.0, preferably in the range of pH 7.0 to 10.0, as that obtained with potassium carbonate.

The molar ratios of permanganate salt, metaperiodate salt and pseudosapogenin are of great importance. Best results were obtained when ratios of 1 mole pseudosapogenin, 8 moles of sodium metaperiodate and 0.13 mole potassium permanganate were used. Increasing the molar ratio of the permanganate salt gave poorer results. However, the reaction is operative at molar ratios other than those which give the best results, especially as regards to the sodium metaperiodate where molar ratios of 2 to 4 times that of the pseudosapogenin were used successfully.

The presence of an inert, water soluble solvent is critical to the operativeness of the invention. Although the disclosed solvents of this category are dioxane, tetrahydrofuran and tertiary butyl alcohol, other water soluble ethers and alcohols which are not attacked by the oxidizing system may be used. Mixtures of these inert, water soluble solvents with water insoluble solvents such as benzene, hexane, heptane and ethyl ether may also be used as vehicles for the pseudosapogenins. When the solution of a pseudosapogenin in inert, water soluble solvent is shaken with an aqueous solution of carbonate, permanganate and metaperiodate salts the desired oxidation reaction commences immediately and rapidly proceeds to completion. Surprisingly, no reaction occurs if the water soluble organic solvent is omitted. Thus shaking a fine dispersion of the pseudosapogenin in the aqueous alkaline oxidizing media gave no reaction. Similarly, attempts to oxidize a benzene solution to pseudosapogenin were unsuccessful.

At the end of the oxidation reaction the desired product, the 16β -acyloxy pregnane, is recovered by extraction of the aqueous system with any inert water insoluble solvent such as benzene, petroleum hydrocarbons, ether, ethyl acetate, and the like. Evaporation of the solvent yields non-crystalline 16β -acyloxy pregnane which is ordinarily immediately hydrolyzed by methods well known to those versed in the art to give the corresponding 16-dehydropregnene. The aqueous layer may be evaporated to a small volume whereupon much of the unreacted sodium metaperiodate crystallizes out and may be recovered by filtration.

The present invention is applicable to all types of pseudosapogenins. Surprisingly, although the pseudosapogenin 20(22) double bond is readily attacked, as illustrated by the following diagram, double bonds in the

3
steroid nucleus, such as the important 5(6) double bond, are not attacked.

Neither are isolated carbonyl groups attacked. The method is applicable to pseudosapogenin diacetates, but in general works more smoothly with the unacetylated forms.

The practice of the present invention is illustrated by the following examples:

EXAMPLE 1

Oxidation of pseudosarsasapogenin

Ten grams of pseudosarsasapogenin were dissolved in 1440 ml. of purified dioxane. This solution was mixed with 2400 ml. of benzene. An aqueous solution was prepared containing 41.0 g. of sodium metaperiodate, 10.0 g. of anhydrous potassium carbonate and 1.2 g. of potassium permanganate in 2650 ml. of water. To this solution was added the benzene-dioxane solution of pseudosarsasapogenin and the mixture vigorously stirred for one hour. The upper solvent layer was drawn off and the residual aqueous layer extracted twice with one liter of benzene each time. The benzene extracts were combined, washed with water and then all the solvent removed in vacuo. The product, 3β - hydroxy-16β-(γ-methyl-δ-hydroxy) valeroxy-pregn-20-one, weighed 11.0 grams and was a yellow viscous oil. The infrared spectrum showed two carbonyl groups consistent with the assigned structure, 1735 cm^{-1} (ester) and 1700 cm^{-1} (20-ketone). Alkaline cleavage with potassium hydroxide in tertiary butanol gave 7.0 g. of 3β-hydroxy-16-pregn-20-one.

EXAMPLE 2

Oxidation of pseudosmilagenin

In a manner similar to Example 1, 10.0 grams of pseudosmilagenin give 10.5 g. of 3β-hydroxy-16β-(γ-methyl-δ-hydroxy) valeroxy-pregn-20-one which on alkaline hydrolysis gave 3β-hydroxy-16-pregn-20-one.

EXAMPLE 3

Oxidation of pseudodiosgenin

Pseudodiosgenin (0.42 g.) was dissolved in 60 ml. of tertiary butanol. The solution was added with vigorous agitation to an aqueous solution containing 1.7 g. of sodium metaperiodate, 0.42 g. of potassium carbonate, and 0.05 g. of potassium permanganate in 110 ml. of water. After shaking five minutes, the mixture was extracted with benzene. On evaporation of the benzene, 0.5 g. of the desired product 3β-hydroxy-16β-(γ-methyl-δ-hydroxy) valeroxy - 5-pregn-20-one was obtained. Acetylation of this compound gave a diacetate identical to the product obtained by the chromium trioxide oxidation of pseudodiosgenin diacetate. Alkaline cleavage of the un-

4
acetylated product gave 3β-hydroxy-5,16-pregnadien-20-one.

EXAMPLE 4

Oxidation of pseudotigogenin

5
In the same manner as described in Example 3, except that tetrahydrofuran was substituted for tertiary butanol, pseudotigogenin was converted to 3β-hydroxy-16β-(γ-methyl-δ-hydroxy) valeroxy-allopregn-20-one which on 10 alkaline hydrolysis gave 3β-hydroxy-16-allopregnen-20-one.

EXAMPLE 5

In the manner described in Example 3 pseudohecogenin was converted to 3β-hydroxy-16β-(γ-methyl-δ-hydroxy) valeroxy-allo pregnan-12,20-dione; 11-oxo-pseudotigogenin gave 3β-hydroxy-16β-(γ-methyl-δ-hydroxy)-valeroxy-allo pregnan-11,20-dione; 12-oxo-pseudodiosgenin gave 3β-hydroxy-16β-(γ-methyl-δ-hydroxy) valeroxy-5-pregn-12,20-dione; 11-oxo-pseudodiosgenin gave 3β-hydroxy-16β-(γ-methyl-δ-hydroxy)-valeroxy-5-pregn-11,20-dione. The 12-oxo-pseudodiosgenin may be prepared according to the process described in an article in J. Org. Chem. 22, 182 (1957) on page 185, column 1, lines 1-4 of the last paragraph, this compound being identical to the compound "pseudogentrogenin diacetate" recited on line 5 of said article. The 11-oxo-pseudodiosgenin may be prepared according to the process described in the copending application of Rothman et al., Serial No. 644, 25 184, filed March 5, 1957, on page 5, lines 20-26. Each of the above 16β-valeroxy compounds had infrared spectra in accordance with the above structures and on alkaline hydrolysis was converted to the corresponding 16-dehydropregnene.

35
The 16β-valeroxy pregnanes (pregnenes) which result from the described alkaline oxidation procedure are new compounds unobtainable by the previously reported acidic oxidation processes. Acidic oxidation of acetylated pseudosapogenins yields acetylated 16β-acyloxy compounds. Any hydrolysis to remove the acetate groups also cleaves the 16-acyloxy ester linkage to produce 16-dehydropregnenes (pregnediенes). Acidic oxidation of unacetylated pseudosapogenins, as mentioned heretofore, results in oxidation of the 3-hydroxy group to give the 3-ketone and also oxidizes the terminal hydroxy group of the 16-acyloxy side chain. Hence, the new compounds can only be obtained by alkaline oxidation procedures.

We claim:

1. A process for oxidizing a pseudosapogenin to its corresponding 16β-acyloxy pregnane comprising dissolving said pseudosapogenin in an inert water soluble organic solvent not attacked by an alkaline oxidizing system, and oxidizing said pseudosapogenin by mixing therewith an aqueous solution containing, based upon weight of pseudosapogenin, about a 2 to 8 molar ratio of a water soluble alkali metal metaperiodate salt, about 0.10 to 0.15 molar ratio of a water soluble alkali metal permanganate salt, and an alkaline agent to maintain a pH above 7.0.
2. The process of claim 1 in which the pseudosapogenin is selected from the group consisting of pseudosarsasapogenin, pseudosmilagenin, pseudodiosgenin, 11-oxo-pseudodiosgenin, 12-oxo-pseudodiosgenin, pseudotigogenin, 11-oxo-pseudotigogenin, and pseudohecogenin.
3. The process of claim 1 in which the pseudosapogenin is pseudosarsasapogenin.
4. The process of claim 1 in which the pseudosapogenin is pseudosmilagenin.
5. The process of claim 1 in which the pseudosapogenin is pseudodiosgenin.
6. The process of claim 1 in which the pseudosapogenin is 11-oxo-pseudodiosgenin.
7. The process of claim 1 in which the pseudosapogenin is 12-oxo-pseudodiosgenin.
8. The process of claim 1 in which the pseudosapogenin is pseudotigogenin.

9. The process of claim 1 in which the pseudosapogenin is 11-oxo-pseudotigogenin.

10. The process of claim 1 in which the pseudosapogenin is pseudohecogenin.

11. 3β - hydroxy - 16β - (γ - methyl - δ - hydroxy) - valeroxy-5-pregn-11,20-dione.

12. 3β - hydroxy - 16β - (γ - methyl - δ - hydroxy) - valeroxy-5-pregn-12,20-dione.

13. The process of claim 1 wherein the alkali metal peroxide is sodium metaperiodate.

14. The process of claim 1 wherein the alkali metal permanganate is potassium permanganate.

15. The process of claim 1 wherein the alkaline agent is potassium carbonate.

16. The process of claim 1 wherein the inert water soluble organic solvent not attacked by an oxidizing system is dioxane.

17. The process of claim 1 wherein the inert water soluble organic solvent not attacked by an oxidizing system is tetrahydrofuran.

10

20

18. The process of claim 1 wherein the inert water soluble organic solvent not attacked by an oxidizing system is tertiary butyl alcohol.

19. The process of claim 1 wherein the alkali metal metaperiodate is sodium metaperiodate, the alkali metal permanganate is potassium permanganate, the alkaline agent is potassium carbonate, and the water soluble organic solvent not attacked by an oxidizing system is tertiary butyl alcohol.
